UNITED STATES PATENT OFFICE.

HENRY S. CRIDER, OF CENTRALIA, KANSAS.

PISTON.

Application filed March 1, 1924. Serial No. 696,258.

To all whom it may concern:

Be it known that I, HENRY S. CRIDER, a citizen of the United States, and a resident of the city of Centralia, in the county of

5 Nemaha, State of Kansas, have invented new and useful Improvements in Pistons, of which the following is a specification.

This invention relates generally to pistons for single acting cylinders, operated either 10 by hydrostatic or pneumatic pressure. Specifically, it pertains to a piston of the type wherein a comparatively pliant packing—such as leather or the like—is utilized, and laterally expanded against the cylinder 15 wall, by the pressure generated in the compression chamber during the compression stroke, to perfect the seal between the piston and cylinder wall, and which recedes therefrom, to permit loading of the chamber, during the suction stroke.

I acknowledge that heretofore pistons of this general class have been produced, in which an inverted, cup-shaped, pliant packing has been used, and its 25 peripheral sealing face laterally expanded against the cylinder wall by fluid pressure generated in the compression chamber. But my improvement differs from these in that instead of making my packing laterally expansible throughout its entire perimeter, to effect the seal, the major portion of its cylinder engaging surface is normally held in sealing contact with the cylinder wall and only a comparatively 30 small sector of its perimeter made laterally expansible and contractible to effect the seal or permit loading of the compression chamber.

I have found by experiment that my improvement conduces to a greater pumping 40 capacity and more efficient operation of the pump than these previous devices, yet possesses all their advantages. This is due to the fact that the smaller, laterally movable 45 sector of the packing is more readily and effectively actuated to effect the seal, by the pressure of the compression chamber, or contracted to permit loading, by the vacuum therein, than when the entire or major portion of its perimeter is expanded or contracted. This results in eliminating a great 50 deal of ineffective movement of the piston and a consequent greater pumping capacity. Also, a much better pump construction is 55 permitted for the reason that a closer fitting and more effective packing is provided over

the major portion of the sealing area; and a thinner, more pliant and hence more efficient packing can be used.

In the accompanying drawings I have 60 illustrated the preferred specific form of my piston and in these drawings—

Figure 1 is a transverse vertical section through my piston and its cylinder;

Fig. 2 is a transverse vertical section 65 through the cylinder, but showing the piston in side elevation;

Fig. 3 is a top plan view of the piston without the packing;

Fig. 4 is a sectional plan view, taken as 70 indicated by the line 4—4 of Fig. 1;

Fig. 5 is a side elevation of the piston without the packing, taken as indicated by the line 5—5 of Fig. 3; and

Fig. 6 is a bottom view of the piston. 75

In these drawings the numeral 10 designates a cylinder, which may, of course, be additionally fitted with any of the well known types of inlet and outlet ports, valves, etc., depending upon the use to 80 which it is put.

My piston has been primarily designed for use in a single acting pump, but need not necessarily be limited to this type as it will be obvious that it may also be utilized in a double acting pump and adaptable for pumping any character of fluid pressure.

The numeral 11 designates my piston centrally mounted upon a piston rod 12, 90 preferably by means of screw-threads 13. In its preferred specific form this piston has a reduced upper end 14 forming an annular shoulder 15, disposed slightly above its bottom 16, and which forms the bottom 95 of an annular channel between the piston and cylinder. While the shoulder 15 may be right angularly disposed, relative to the axis of the piston, I preferably make it inclined, relative to this axis, for reasons 100 which I will later explain.

The peripheral face 17 of the piston, intermediate the shoulder 15 and the bottom 16 forms a comparatively close sliding fit in the internal bore 18 of the cylinder 10, 105 but, of course, this fit is not air tight.

A flattened side 19 is formed on the upper reduced portion 14, of the piston 11, above the shoulder 15, substantially as shown. The width of this flattened side may be varied 110 within certain limits to adapt the piston to different uses and different weight and types

of packings; but ordinarily the extent of its area will be relatively small compared with the size of the piston. In determining its size consideration will be given to the thickness of the packing and its circumferential area and the area of the surface 19 then determined to give the most effective results from the standpoint of instantaneous actuation, to either expand or contract the sector 10 of the packing overlying it at the start of either the compression or suction stroke.

An aperture 20 extends through the piston 11 from its bottom face 16 to the flattened face 19 and preferably this aperture will 15 communicate with the latter along its vertical center, as shown in Figs. 3 and 5.

An inverted, cup-shaped, pliant packing 21 is secured over the upper reduced end 14 of the piston 11, so that its free edge 22 will 20 surround this reduced end and fill the space between its periphery and the cylinder bore 18. The packing 21 may be formed of any suitable material, but preferably it will be made of a pliant leather, formed substantially as shown. In this form it may be rigidly secured in place over the upper end of the piston by means of a nut 23 screw-threadedly mounted on the lower end of the piston rod 12. Other ways of securing the 30 packing to the piston may be utilized so long as they are adaptable to securing this type of inverted, substantially cup-shaped packing to the piston, in the manner shown.

The packing 21 will be of such thickness 35 that when confined between the periphery 24, of the reduced end 14, and the bore 18 of the cylinder 10, it will be slightly compressed so as to form a close sealing fit there-in entirely around the peripheral face 24, except over the flattened side 19.

While in this form of my piston I will depend mainly upon the thickness of the packing 21 to form a close sealing fit in the bore of the cylinder I also take advantage 45 of the pressure generated in the compression chamber C to effect an expansion of the lower peripheral edge 22 of the packing 21, by cutting the latter at an acute angle substantially conformable to the inclination of the shoulder 14, as shown in Fig. 1; so that 50 any fluid pressure passing around the lower peripheral face 17 of the piston will pass into the space 25, left between the lower edge of the packing 21 and the shoulder 15 to 55 assist in its sealing effect. With this type of piston and the use of a packing which will normally have a close sealing fit in the cylinder surrounding the major portion of the periphery of the piston, this may be small 60 or possibly negligible, but I provide this means for taking advantage of it if such be possible.

In the operation of my piston, the sealing of the fluid pressure in the cylinder is normally effected around the periphery of the 65

piston, except over the surface 19, by compressing the packing 21 between the peripheral face 24 and the cylinder bore 18. The packing 21 being pliant, during the compression stroke the pressure in the compression chamber C passes through the aperture 20 to the space between the flattened face 19 and the adjacent sector of the packing, forcing the latter outwardly into sealing engagement with the cylinder bore. During the 75 suction stroke the vacuum in the compression chamber created by a slight upward movement of the piston will immediately draw this sector of the packing 21 extending over the surface 19 inwardly, permitting fluid pressure to pass this side of the piston and load the compression chamber. As the sector of the packing 21 extending over the flattened surface 19 is comparatively small this will be very readily actuated 80 towards or away from the surface 19 by the vacuum or pressure in the compression chamber C, as the case may be; and by reason of this quick actuation considerable waste or ineffective movement of the piston 90 in either direction is eliminated. Furthermore, expansion or contraction of this comparatively small sealing area of the packing 21 conduces to a more positive and efficient 95 opening or closing of this fluid pressure passage past the piston.

While I have described in this preferred specific form of my improvement the upper reduced end 14 of the piston, the shoulder 15 and lower peripheral cylinder engaging portion 17, forming when combined with the cylinder 10, an annular channel in which the packing 21 is carried, it is obvious that the broad principles of my improvement, which include the pliant packing and flattened surface 19, need not be limited by this precise construction, as the shoulder 15 and enlarged annular portion 17 may be eliminated and the flattened side 19 used in conjunction with a straight cylindrical piston. 105 Other changes may also be made which will ordinarily occur to those skilled in the art.

Having described my invention, I claim:

1. A cylindrical piston having a flattened side and a pliant annular packing, carried by said piston, extending over said flattened side. 115
2. A cylindrical piston having a flattened side and a pliant cup-shaped packing extending over one end of the piston and over said flattened side. 120
3. A cylindrical piston having a flattened side and a pliant inverted, cup-shaped packing extending over and secured to one end of the piston so its free edge surrounds the 125 piston and extends over said flattened side.
4. A piston having a reduced end forming a peripheral shoulder thereon, a flattened side on said reduced end, an aperture extending through the piston forming a pas- 130

sage between its bottom and said flattened side, and a pliant packing secured over said reduced end with its free edge adjacent said shoulder.

5. A piston having a reduced upper end forming a peripheral shoulder thereon, a flattened side on said reduced end, an aperture extending through the piston forming a passage between its bottom and said flattened side, and a pliant, inverted cup-shaped packing extending over said reduced end and secured thereto at its top so its free edge surrounds the piston adjacent said shoulder and overlies said flattened side.

10. A piston having a reduced upper end and a pliant, inverted cup-shaped packing extending over said reduced end and secured thereto at its top so its free edge surrounds the piston adjacent said shoulder and overlies said flattened side.

15. A piston having a reduced upper end and a downwardly inclined peripheral shoulder thereon, a flattened side on said reduced end above said shoulder, an aperture extending through said piston forming a passage between its bottom and said flattened side, and a pliant packing secured to the upper end of said reduced portion to extend over said reduced end and flattened side with its free edge adjacent the shoulder, said packing edge being inwardly beveled to conform substantially to the inclination of the shoulder.

7. The combination with a cylinder of a piston having a reduced upper end forming a peripheral shoulder thereon and an annular channel between said end and the

cylinder wall, a flattened side on said reduced end above the shoulder, an aperture extending through the piston forming a passage between its bottom and said flattened side, and a pliant packing secured in said channel adjacent its top with its free edge adjacent said shoulder and to overlie said flattened side.

8. The combination with a cylinder of a piston having a reduced upper end forming a downwardly inclined peripheral shoulder thereon, an annular channel between said end and the cylinder wall, a flattened side on said reduced end above the shoulder, an aperture extending through the piston forming a passage between its bottom and said flattened side, and a pliant, inverted cup-shaped packing extending over said reduced end and secured to its top, the free edge of said packing extending into said channel to adjacent the shoulder, said edge being inwardly beveled to conform substantially to the inclination of the shoulder.

In witness that I claim the foregoing I have hereunto subscribed my name this 14th day of January 1924.

HENRY S. CRIDER.
